UNITED STATES PATENT OFFICE.

ARTHUR W. BROCK, OF ALMA, MICHIGAN.

HEATING AND VENTILATING DRUM.

SPECIFICATION forming part of Letters Patent No. 701,286, dated June 3, 1902.

Application filed March 31, 1902. Serial No. 100,701. (No model.)

To all whom it may concern:

Be it known that I, ARTHUR W. BROCK, a citizen of the United States of America, residing at Alma, in the county of Gratiot and 5 State of Michigan, have invented certain new and useful Improvements in Heating and Ventilating Drums, of which the following is a specification, reference being had therein to the accompanying drawings.

10 This invention relates to new and useful improvements in heating-drums, and applies to that class intended to be used in connection with furnaces and stoves through which the products of combustion are to be passed 15 for the purpose of obtaining the benefit by radiation of the heat therefrom, and it may either be applied in the room above the stove or furnace or in the same room, if desired, and the invention is designed as an improvement

20 upon my prior patent, No. 458,013, of August 18, 1891, in which patent the circulation in the upper heating-chamber was sluggish on account of the short distance the air had to travel from the intake to the outlet and 25 the short time it had to become thoroughly heated; and one of the objects of my invention is to overcome this difficulty by carrying the intake-pipe for the upper chamber down through the lower chamber, so that the air

30 will become heated in the lower chamber, thus having an opportunity to give off some of this heat in passing from the lower to the upper chamber, and then be finally reheated again in the upper chamber before being dis-

35 charged into the room, thereby adding greatly to the heating capacity of the drum, besides obtaining a much more rapid circulation of the air, a further object of the invention being to provide ready access to the interior of 40 the drum for the purpose of cleaning the same.

To this end, the invention consists in the peculiar construction, arrangement, and combination of parts, all as more fully herein-after described, and shown in the accompanying drawings, in which—

45 Figure 1 is a side elevation of my improved heating-drum with the upper and lower sections shown as detached; Fig. 2, a vertical central section therethrough; Fig. 3, a vertical central section through the lower portion

of the heating-drum, illustrating a modified construction.

A is the main inlet-flue, by means of which the drum is connected with the smoke-outlet from the stove or furnace. 55

B and C are the vertical branches thereof, the former forming a direct passage and the other an indirect down-passage.

E is the lower smoke-chamber, into which the indirect passage C communicates, and D 60 is the upper smoke-chamber, into which the direct passage communicates.

F is a removable hood forming the top portion of the upper chamber D, and H is the smoke-exit from said chamber, and I is a hot-air chamber suspended within the hood F by means of the flues J J, connecting said chamber with the atmosphere. 65

K is an air-inlet into the bottom of the hot-air chamber and which fits in the flue K' 70 when the hood is secured upon the upper chamber, and which flue extends clear through and into proximity with the hopper-shaped bottom of the lower chamber, a detachable section K² being sleeved on the lower end of 75 said flue and extending through the bottom of said chamber and preferably carrying a suitable damper arrangement hereinafter more fully described.

L represents three hot-air flues passing vertically through the lower chamber E, and P represents two smoke-flues leading from the top of the lower chamber into the bottom of the upper chamber. 80

Q is a partitioned wall in the lower chamber, reaching down from the top to near the bottom of said chamber, so as to cause the products of combustion to be carried down to the bottom of said chamber before they can pass up through the smoke-flues P, and thus 85 thoroughly heat the air-flues. The hopper-shaped bottom of the chamber E is provided with a central aperture for the reception of the detachable section K² of the central air-flue and a concentric series of openings S, and 90 T is an inclined collar formed with a corresponding series of openings carried by the extension K² and adapted to register with the openings S, and V is a downward extension 95 forming a handle for the purpose of opening 100

or closing said openings to regulate the draft, as desired.

W represents legs integral with the lower portion of the drum, and G is a damper in 5 the direct branch B.

In practice if the damper is placed in the position shown in Fig. 2 the products of combustion from the stove are directed through the branch C into the lower chamber E and 10 are compelled to pass to the bottom thereof below the partition Q and then upwardly through the flues P into the upper chamber and through the exit-flue into the chimney. During this passage it will be seen that the 15 hot gases will pass around the pipes K' and L in the lower chamber and thoroughly heat the same, thus causing the air to enter the bottom of these pipes and be discharged in a heated condition at the top, that, however, in 20 the pipe or flue K' passing on up into the hot-air chamber and simply giving off its heat by radiation in passing from the lower into the upper chamber, during which time it will have acquired sufficient momentum to 25 carry it up through the hot-air chamber and into the room after having again been thoroughly reheated. The gases of combustion in passing into the upper chamber will envelop the hot-air chamber and thoroughly 30 reheat the air therein which may have become cooled in passing from the lower into the upper chamber, after which the hot air is discharged into the room through the flues J.

If the damper G is turned in the position 35 shown in dotted lines in Fig. 2, the hot gases from the stove will directly enter into the upper chamber and simply heat the air in the chamber thereof, and by adjusting the damper into any intermediate position part of 40 the gases may be compelled to pass through the indirect branch into the lower chamber and through that into the upper chamber, while the rest finds its exit directly into the upper chamber, and the amount of hot air 45 may be thus regulated to satisfy the circumstances.

In Fig. 3 I have shown a modified construction, in which the lower ends of the air-flues L project out through the side of the casing, 50 which may be connected by separate pipes with the outside air, thus bringing constantly fresh air into the room and heating it to a moderate temperature. At the same time the rotating collar or damper T may be turned to 55 open the registering holes whenever the air becomes foul and the foul air drawn from the room into the chamber E and be carried away with the hot gases into the chimney. This ventilation will be especially effective when the 60 damper G is open for direct draft and the damper G' closed. It will further be seen that the removable hood F permits of cleaning out the soot and dirt in the upper chamber and brushing it into the lower chamber

through the flues P, and from which the soot 65 is removed by taking out the pipe K', a suitable receptacle being placed therebeneath to catch the debris, after which the pipe K' may be put back into place and the device is ready for further operation. I may preferably make the lower chamber in sections, as 70 shown, so that it may readily be taken apart at any time should occasion demand.

Having thus fully described my invention, what I claim is—

1. In a heating-drum, the combination of a vertical flue, an inlet connection therein, heating-chambers connecting with the top and bottom of said flue, a damper in said vertical flue, independent air-flues in said lower chamber, an air-reheating chamber communicating with the atmosphere in said upper chamber and an inlet-pipe for said chamber passing through said lower chamber, for the purpose described. 75

2. In a heating-drum, the combination of a vertical flue, an inlet connection therein, heating-chambers connecting with the top and bottom of said flue, a damper in said vertical flue, independent air-flues in said lower chamber, a hot-air chamber in said upper chamber, air inlet and outlet flues for said chamber, said inlet-flue extending down through the bottom of the upper chamber and partially through the lower chamber and a detachable 90 extension projecting through the bottom of the lower chamber, sleeved on said flue, for the purpose described. 95

3. In a heating-drum, the combination of a vertical flue, an inlet connection therein, heating-chambers connecting with the top and bottom of said flue, a damper in said vertical flue, independent air-flues in said lower chamber, a hot-air chamber in said upper chamber, air inlet and outlet flues for said chamber, said inlet-flue extending down through the bottom of the upper chamber and partially through the lower chamber, a damper in said flue intermediate said upper and lower chambers, and a downward extension projecting through the bottom of the lower chamber and carrying a ventilating-register. 100 105

4. In a heating-drum, the combination of a vertical flue, an inlet connection therein, heating-chambers connecting with the top and bottom of said flue, a damper in said vertical flue, independent air-flues in said lower chamber, a hot-air chamber in said upper chamber, air inlet and outlet flues for said chambers, said inlet-flue extending down through the bottom of the upper chamber and partially through the lower chamber and a detachable extension projecting through the bottom of the lower chamber sleeved on said flue, a flaring collar on said extension forming a stop and provided with openings adapted to register with openings in the bottom of the lower chamber to form a register and an 115 120 125

outwardly-flaring portion below said collar adapted to form a handhold for actuating said register.

5. In a heating and ventilating drum, the combination of an upper direct smoke-chamber D and a lower indirect smoke-chamber E, the main inlet-flue A having direct and indirect branches B and C respectively leading into said chambers, the regulating-damper G in the direct branch, the air-heating chamber in the upper smoke-chamber provided with air inlet and outlet flues, and the air-inlet flues passing through the lower chamber formed with lateral extensions at their 15 ends for the purpose described.

6. In a heating and ventilating drum, the combination of an upper direct smoke-chamber and a lower indirect smoke-chamber, the main inlet-flue having direct and indirect 20 branches respectively leading into said chambers, the regulating - damper in the direct branch, the air-heating flues passing through the lower chamber, the air-heating chamber in the upper chamber provided with outlet 25 and inlet flues, the air - inlet flue passing through the lower chamber and connected at

its upper end with the air-heating chamber and the detachable extension sleeved on the lower end of said flue.

7. In a heating and ventilating drum, the 30 combination of an upper direct smoke-chamber and a lower indirect smoke-chamber, the main inlet-flue having direct and indirect branches respectively leading into said chambers, the regulating - damper in the direct 35 branch, the air-heating flues passing through the lower chamber, the air-heating chamber in the upper chamber provided with air inlet and outlet flues, said inlet - flue passing through the lower chamber and connecting 40 the air-heating chamber with the atmosphere and a rotatorially-adjustable collar carried by the lower end of said flue and formed with openings adapted to register with openings in the bottom of the lower chamber to form 45 a ventilating-register.

In testimony whereof I affix my signature in presence of two witnesses.

ARTHUR W. BROCK.
